Primary Examiner — Patricia A Palasik*(74) Attorney, Agent, or Firm* — Novick, Kim & Lee, PLLC; Jae Youn Kim; Jihun Kim(57) **CLAIM**

We claim the ornamental design for a gear for actuator, as shown and described.

DESCRIPTION

FIG. 1 is a perspective view of a gear for actuator, showing our new design;

FIG. 2 is a top plan view thereof;

FIG. 3 is a bottom plan view thereof;

FIG. 4 is a left side elevational view thereof;

FIG. 5 is a right side elevational view thereof;

FIG. 6 is a front elevational view thereof; and,

FIG. 7 is a rear elevational view thereof.

1 Claim, 6 Drawing Sheets(56)
